SCARF HOLDER OR SIMILAR ARTICLE

Joseph Wolff, New York, N. Y.

Application July 22, 1949, Serial No. 4,086

Term of patent 3½ years

(Cl. D17—3)

To all whom it may concern:

Be it known that I, Joseph Wolff, a citizen of the United States of America, residing in New York city, county of New York, and State of New York, have invented a new, original, and ornamental Design for a Scarf Holder or Similar Article, of which the following is a specification, reference being had to the accompanying drawing, forming part thereof, wherein,

I claim:

The ornamental design for a scarf holder or similar article, substantially as shown,

JOSEPH WOLFF.
